UNITED STATES PATENT OFFICE.

ULRIC O. HUTTON, OF MILWAUKEE, WISCONSIN, ASSIGNOR TO THE CUTLER-HAMMER MFG. CO., OF MILWAUKEE, WISCONSIN, A CORPORATION OF WISCONSIN.

APPARATUS FOR EFFECTING AND REGULATING A FLOW OF FLUID.

Application filed August 10, 1925. Serial No. 49,357.

This invention relates to apparatus for effecting and regulating a flow of fluid. More particularly, my invention relates to a thermal expansion aspirator or pump.

5 In certain fluid testing devices and the like it is necessary to substantially continuously extract or supply from a given source a quantity or sample of the fluid to be tested; and one object of my invention is to provide improved apparatus for accomplishment of such purpose.

Another object is to provide simple and efficient thermally operated and controlled means of the character aforementioned.

15 Another object is to provide an improved pump or aspirator for supplying relatively small quantities of fluid.

Another object is to provide novel means for utilizing the physical characteristics of 20 thermally expansible fluids.

Another object is to provide for regulation of thermally operated devices of the above character.

Other objects and advantages of the invention will hereinafter appear.

The accompanying drawing illustrates certain embodiments of the invention which will now be described, it being understood that the embodiments illustrated are susceptible of modification without departing from the scope of the appended claims.

In the drawing, Figure 1 is a vertical sectional view of an aspirator or pump constructed in accordance with my invention, certain of the associated elements being shown diagrammatically, and

Fig. 2 is a similar view of a modified form of my invention.

The device illustrated in Fig. 1 comprises a chamber or receptacle 5 of any suitable form adapted to be normally filled with an expansible fluid, such as air or gas, said chamber having a top or cover 6 sealed or otherwise tightly fitted and secured thereto.

45 Cover 6 preferably consists of a plate or block of insulating material and extending therethrough is a screwthreaded bolt or rod 7, the outer end of which serves as a binding post or terminal; and to the inner end thereof is secured by rivets 8 or in any other suitable manner, a thermostatic element 9 of the bimetallic type. The free end of element 9 is provided with a contact portion 10 which is movable into and out of engagement with a stationary contact 11, the latter

being supported by a metallic screw or bolt 12 attached to the cover 6. One end of a heating element or resistor 13 is electrically connected to the bolt 12, the other end of the former being similarly connected to a screwthreaded bolt or rod 14 which extends outwardly through cover 6 to form a second binding post or terminal. Wires 15 and 16 may lead to any suitable source, such as a battery B, for supplying a current which is 65 of predetermined value, but which may be varied, if desired, by means of a suitable rheostat R, for a purpose hereinafter described.

Communicating with receptacle 5 at the 70 lower end thereof is a pipe or conduit 17, said pipe being provided at its lower end with long and short branches 18 and 19, respectively. Branch pipe 18 extends below the level of a body of liquid 20, such as mercury, carried by a valve chamber 21. Chamber 21 has a tight fit with pipe 18, and is also provided above the level of liquid 20 with an outlet opening or passage 22, including a tubular projection or nipple 23. 80 The short branch pipe 19 has a tight fit with a valve chamber 24 and opens thereinto above the level of a body of liquid 25, said chamber being also provided with an inlet opening or passage 26 including a tubular 85 projection 27 and a tubular member 28 extending downwardly below the level of liquid 25. The inlet opening or projection 27 may be connected with a suitable source of gas or other fluid which is preferably at 90 substantially atmospheric pressure, whereas the outlet opening or projection 23 is connected with a testing device, such as a carbon dioxide or carbon monoxide recorder (not shown), to which a substantially continuous sample of the fluid is to be supplied.

The receptacle 5 may be provided externally with a plurality of fins or projections 29 to accelerate cooling of the contained fluid under conditions hereinafter described. 100

Operation of the device illustrated in Fig. 1 is as follows: With the parts 23 and 27 connected as aforescribed, the heater circuit is closed by means of a suitable switch S, whereupon the expansible fluid contained within the receptacle 5 is gradually heated to effect expansion thereof. The resulting increase in pressure of the fluid effects discharge of a quantity of fluid through the branch pipe 18, valve chamber 21 and outlet 110

passage 22,—mercury valve 20 acting to prevent reverse flow of fluid through branch pipe 18. Upon attainment of a given temperature within receptacle 5, the thermostatic element 9 is adapted to act in the well known manner to effect disengagement of contacts 10 and 11, thereby interrupting the energizing circuit of heater 13. The fluid contained within receptacle 5 gradually cools, and the cooling action is accelerated by the radiating fins or projections 29 in an obvious manner. Reduction in pressure or contraction of the fluid due to cooling thereof creates a partial vacuum within the receptacle 5, and a quantity of the fluid to be tested is drawn from the source into and through the valve chamber 24. When the interior of receptacle 5 has cooled to a predetermined temperature thermostat 9 effects re-engagement of contacts 10 and 11 thereby closing the circuit of heater 13 to again cause expansion of the contained fluid and discharge of a quantity of fluid through outlet passage 22. The foregoing cycle of operation is repeated continuously, thus providing an intermittent intake of the test fluid and discharge thereof at the desired point.

By suitably proportioning the heating element 13 and the cooling area of the receptacle 5 the pump or aspirator may be made to operate at any one of a wide range of speeds, such as once a second or as slow as once in five minutes. Similar variations in the rate of operation of the device may be obtained by adjustment of the rheostat R.

By the arrangement aforescribed I am able to utilize the pulsating effect of the alternately heated and cooled fluid in a novel manner. If desired the partially closed receptacle or container 5 may be initially filled with a quantity of the fluid to be tested; but this is not necessary, inasmuch as the body of fluid therein acts largely as a piston or diaphragm to effect passage of the test fluid through the one-way valves, as shown; whereas any contamination or dilution of the test fluid with the fluid in the receptacle is practically negligible.

In the modification illustrated in Fig. 2 the numeral 30 designates a receptacle or container having a pipe or conduit leading from the upper end thereof. Said pipe is provided with one or more convolutions or corrugations 31, 32 below the upper horizontal portion 33 thereof, for a purpose herein-after described, whereas the other end of said pipe leads into a valve chamber 34. Valve chamber 34 is provided with upper and lower inwardly extending annular flanges 35 and 36 forming seats for the ball or check valves 37 and 38, respectively. As shown, the flanges 35 and 36 are downwardly inclined to act as guides for seating the valves. The ball valve 37 normally closes the outlet opening 39 of chamber 34, whereas

ball 38 normally closes the inlet opening 40 of said chamber. Registering with the inlet opening 40 is a tubular projection or nipple 41 for connection with a suitable source of fluid supply; whereas a similar nipple 42 provides for connection of the outlet end of the valve with a suitable fluid testing device or the like.

Located at a suitable point within the receptacle 30 is a fluid thermostatic device 75 comprising a container 43 for air or other gaseous fluid, having a conduit or pipe 44 leading therefrom to a fluid pressure operated valve. Said valve preferably comprises a U-tube 45 having at one side an enlarged 80 portion 46 and communicating at the other side with a plurality of branch pipes or tubes 47 and 48. Pipe 47 is connected with a suitable source of combustible fluid, such as gas; whereas in the full line position of 85 the body of mercury or other liquid 49, the pipe 47 is in direct communication with pipe 48. Pipe 48 in turn leads to a suitable gas burner or heating device 50 located under the chamber 30, said burner having associated therewith a pilot burner or tube 51, connected to pipe 47. The flame 52 of the burner is adapted to heat the fluid within receptacle 30, and due to the increase in fluid pressure a quantity of fluid is expelled 90 through the outlet opening 39. The rise in temperature within receptacle 30 also causes expansion of the air or other fluid within container 43, and the increased pressure thereof displaces the body of mercury 49 100 from the full line position shown to the position shown in dotted lines, thus cutting off the supply of gas from pipe 47 to burner 50.

Upon cessation of the heating effect of burner 50, the fluid within receptacle 30 tends to cool down, and I preferably provide for acceleration of the cooling action by means of a water or other liquid cooling jacket 53 for said receptacle; said jacket having inlet and outlet openings 54 and 55, respectively, to be connected with a continuous supply of cooling liquid as desired. During cooling, the fluid within receptacle 30 condenses or contracts, thus creating a 115 partial vacuum which effects opening of inlet valve 38 and withdrawal of a quantity of fluid from the source, which is preferably at substantially atmospheric pressure. The pipe leading from the upper end of container 30 is preferably of such length between the horizontal portion 33 thereof and valve chamber 34 as to accommodate the entire charge of fluid drawn through inlet opening 40. This arrangement prevents the fresh charge of fluid from being drawn into chamber 30. During the aforementioned cooling operation the fluid within container 43 is likewise cooled and the pressure thereof reduced, thus permitting return of the body of mercury 49 to the normal position illus- 125 130

trated. The combustible fluid is then again permitted to flow to the burner 50, and the same is ignited by the pilot burner 51, in an obvious manner. Thereafter the fluid in receptacle 30 expands and forces a charge of the test fluid through the outlet opening 39 to the desired point of use. At the same time, the thermally expansible fluid in container 43 is again heated to effect cutting off of the supply of gas to burner 50 as aforescribed, and the cycle of operation is repeated.

As will be apparent the device illustrated in Fig. 2 may also be employed to pump a liquid, instead of a gas, inasmuch as the arrangement of the intake pipe 31 will prevent passage of the normal charge of fluid into the receptacle 30. Moreover, either type of cooling means disclosed may be employed with the respective devices illustrated. Instead of employing the thermoelectric circuit making and breaking device 9, as shown in Fig. 1, I may employ any other suitable means for this purpose, such as a motor operated contact device or a common form of light flashing device. Similarly other types of check valves or one-way valves may be substituted for those illustrated in the drawing.

If desired, the rate of heating of the fluid, and consequently the rate of operation of the device as a whole, may be changed by adjustment of a suitable control valve 56 in the pipe 48, Fig. 2.

What I claim and desire to secure by Letters Patent is:

1. In a device for effecting a flow of gaseous fluid, the combination with a source of such fluid at substantially atmospheric pressure, of means for intermittently withdrawing a predetermined quantity of fluid from said source and alternately discharging the same at a given point, said means comprising a suction operated inlet valve and a pressure operated outlet valve, a gaseous fluid chamber associated with said valves, adjustable means for heating said chamber to effect discharge of fluid through said outlet valve, thermally responsive means for periodically interrupting the supply of heat to said chamber, and means for thereafter cooling said chamber to create a suction for operation of said inlet valve.

2. Apparatus of the character described comprising a receptacle, a thermally expansible gaseous fluid normally filling said re-

ceptacle, adjustable means for intermittently heating said fluid, said means comprising a thermostatic device responsive to given temperature conditions of said fluid, and means for utilizing the expansion and contraction of said fluid under the aforementioned conditions to effect a flow of another fluid, said means comprising a plurality of one-way valves to be subjected respectively to pressure and suction conditions in said receptacle.

3. A thermal expansion aspirator comprising a receptacle, a quantity of thermally expansible gaseous fluid filling said receptacle, means for heating said fluid to effect expansion thereof, thermally responsive means for interrupting the supply of heat to said fluid to permit cooling thereof, and a source of gaseous fluid at substantially atmospheric pressure adapted to be subjected to pressure and suction conditions in said receptacle for effecting a flow thereof.

4. A thermal expansion aspirator comprising a receptacle, a quantity of thermally expansible gaseous fluid in said receptacle, electrical means for heating said fluid to effect expansion thereof, bimetallic thermostatic means for interrupting the supply of heat to said fluid to permit cooling thereof, and a plurality of one-way valves responsive respectively to pressure and suction conditions in said receptacle for controlling the intake and discharge of another fluid subjected to said pressure and suction conditions.

5. A thermal expansion aspirator comprising a receptacle, a quantity of thermally expansible gaseous fluid within said receptacle, an electric heating element located within said receptacle, means for varying at will the value of current supplied to said element, a bimetallic thermostatic element also located within said receptacle and adapted to make and break the energizing circuit of said heating element under given temperature conditions within said receptacle, and means for relieving the pressure within said receptacle under conditions of alternate heating and cooling of the fluid contained therein, said means comprising a source of gaseous fluid at substantially atmospheric pressure and a plurality of one-way mercury valves for controlling the intake and exhaust of said fluid to and from said receptacle.

In witness whereof, I have hereunto subscribed my name.

ULRIC O. HUTTON.
